UNITED STATES PATENT OFFICE

2,547,138

TOOL FOR REMOVING RADIO TUBES AND VIBRATORS

Arthur C. Pothier and Arnold C. Howe,
Portland, Maine

Application June 29, 1948, Serial No. 35,838

2 Claims. (Cl. 254—131)

1

The invention relates to a tool particularly adapted to the removal of radio tubes, vibrators, and similar objects which usually must be removed under very trying conditions.

One of the objects of the invention is to provide a device of this character which will quickly and easily remove radio tubes and the like under most difficult conditions.

Another object of the invention is to provide a device of this character which will quickly and easily remove radio tubes and the like regardless of how limited the working space may be.

A further object of the invention is to provide a device of this character which will quickly and easily remove radio tubes and the like when in highly heated condition during operation, and regardless of the corroded condition of the parts.

Still another object of the invention is to provide a device of this character which will quickly and easily remove even the most fragile glass tubes without any danger of injury to the tube or the operator.

A further object of the invention is to provide a tool of this character which will quickly and easily remove radio tubes, vibrators and the like, whether such tubes or vibrators are cylindrical throughout or have enlarged portions.

Another object of the invention is to provide a device of this character in which the parts cannot become accidentally separated, though the parts are easily assembled and may be quickly disassembled when desired.

Still another object of the invention is to provide a device of this character in which a smooth, efficient, and durable tool is insured by reason of a particular connection between the operating lever and other parts.

Various other objects and advantages of the invention will be apparent to those skilled in the radio art from the following description, when taken in connection with the accompanying drawings, in which:

Figure 1 is a plan view of the tool in combination with a fragmentary representation of any conventional radio;

Figure 2 is a perspective view of the tool positioned to remove a tube;

Figure 3 is a side elevational view of the tool in combination with a tube it has lifted from place; part of the tool being shown in section to more clearly illustrate the structure;

Figure 4 is a fragmentary side elevational view of the device, with parts broken away; and

Figure 5 is a detail perspective view of the foot of the tool.

2

The removal of radio tubes, vibrators, etc., has long been a problem. The tubes often have to be removed when in highly heated condition, for example, when in operation, and during tests on the production line. But whether hot or cold, tubes are often very difficult to remove because of corrosion of the parts. Then too, the space within which the tool can operate is usually extremely limited, and most tubes are of fragile glass.

The present application is a continuation in part of our application Serial Number 755,564, filed June 19, 1947, patented December 13, 1949, No. 2,491,132. Prior to the invention disclosed in said application no tool had been devised which would quickly and easily remove tubes under the difficult conditions mentioned above, and particularly fragile glass tubes. It will be understood that in the use of the word "tube" herein and in the claims or elsewhere, it is intended to include not only radio tubes used in home sets, automobile sets, aviation sets, radar, etc., but also vibrators and such devices used in such sets.

25 Referring now to the drawings, numeral 1 indicates a lever and numeral 2 indicates a lower fixed hand grip; the forward ends of these members being hingedly connected to a link 3.

Soldered, welded, or otherwise rigidly attached 30 and depending from the lower hand grip 2 is a relatively long, slender tubular member or sleeve 4. Numeral 5 indicates a foot which is welded to or integral with the lower end of the tubular member. As best shown in Figure 5, the toe of the foot may be lined, as indicated by numeral 5', or otherwise roughened in any desired manner to provide a better gripping surface.

Housed within this tubular member is a spindle or plunger 6, which preferably has a pointed lower end 6'. This pointed lower end makes a minute indentation in the floor of the chassis, in the operation of the tool, and thus prevents any slippage, and avoids the necessity of any pre-arranged construction of the chassis floor to hold

45 the tool against slippage. And it will also be noted that as the lower portion of the spindle and its pointed end are entirely housed within the sleeve 4, until the tool is actually operated to lift the tube, there is nothing to prevent the foot from being quickly arranged in the desired position for tube removal which obviously, would not be the case if the lower end of the spindle and the pointed end projected from the foot during the positioning of the foot.

50 55 The lever 1 and handle 2 are shown as solid,

and the lever is provided with a generally cylindrically cavity or bore 7 having a seat 8 at its lower end to cooperate with a ball-shaped head 9 provided on the upper end of the spindle 6, as shown in Figures 3 and 4. The upper portion of the cavity or bore is threaded at 10 to receive a screw 11 which has a flat lower end. This screw is preferably provided with an irregularly shaped cavity 12 to receive the end of any appropriate tool for seating and removing the screw. When the lever 1 is in its upwardly inclined position, the lower end of the screw is slightly spaced from the ball-shaped head 9 of the spindle, as shown in Figure 4. Below the seat 8 the lever 1 has an appropriately cut-away portion 13 to permit freedom of relative movement between the lever and the spindle, and in the specific form illustrated the spindle at this point is slightly tapered toward the ball-shaped head 9.

Loosely mounted on the upper end of the spindle 6, below the ball-shaped head, is an elongated washer 14, and as shown in Figure 2 this washer is curved in cross-section to make a neat fit with the curvature of the lever. Between this washer and the hand grip 2 a coil spring 15 is mounted on the spindle 6.

In connection with the construction described immediately above, and best shown in Figure 4, it will be noted that the coil spring normally forces the spindle 6 and the lever 1 upwardly, so that the lower end of the spindle is normally housed within the sleeve 4, and that free upward movement of these parts is limited by the side of the spindle abutting against the wall of the cut-away portion 13. It will also be noted that by the construction described the parts cannot become accidentally separated, but that to disassemble the parts it is only necessary to remove the screw 11 and withdraw the spindle 6.

Numeral 16 refers to a radio tube which may be of any desired shape and type, and the tube may be entirely of glass, or of glass with a metal base, or of any other material of which radio tubes are made. And, of course, the tube may be mounted in position by any of the well known means. In the specific form illustrated the tube is of glass with a metal base 17, and the base is provided with a depending centrally arranged plug 18 around which are a plurality of depending fingers 19. In mounting the tube in operative position the plug 18 and fingers 19 are inserted in appropriate openings 20 and 21, respectively, as is well known.

While the tubes are easily inserted in a set, it is often most difficult to remove them, because of the small space in which a tool can operate, and it is particularly difficult when the parts have become corroded, with resulting verdigris deposits, etc. And the problem of removal is aggravated, of course, when the tubes must be removed when high heated, as is often the case.

Before describing the removal operation, attention is called to the shape of the foot 5 relative to the tubular member or sleeve 4. The drawings illustrate the tool in use with tubes or vibrators which are cylindrical in shape. And by reference to the drawings, particularly Figures 2 and 3, it will be noted that when the tool is in vertical position the foot inclines slightly downwardly from the tubular member 4, so that the foot is readily inserted beneath the tube or vibrator.

However, radio tubes, vibrators, and the like are often made of such shape that an upper portion thereof is of greater diameter than the lower portion or base. The present invention is par-

ticularly adapted to the removal of tubes and the like of such shapes. As mentioned hereinbefore the foot 5 inclines slightly downwardly from the sleeve 4, and thus the tool may be inclined to the vertical, to clear an enlarged part of the tube or the like, and foot 5 will still be flat upon the floor of the chassis, in proper position to be inserted for the removal operation.

This is best understood by reference to Figure 3. Let it be assumed that the parts in that figure are shown prior to the operation of the tool to lift the tube. The tool is in its vertical position and the foot is inclined downwardly so that its toe rests on the floor of the chassis, ready to be inserted beneath the tube, which is shown in this instance as of the cylindrical type. But suppose the tube is bulged or flared or any shape having an upper portion of greater diameter than the lower portion or base. In that event it is only necessary to incline the tool slightly outwardly from the vertical position, as far as necessary to clear the enlarged part of the tube, or until the entire foot rests upon the chassis floor, whereupon the toe still remains in position to be inserted beneath the tube. Thus it is clear that even in the restricted spaces within which the tool operates, it is particularly designed to remove tubes and the like regardless of the shape thereof.

The operation of the device in removing tubes, vibrators, etc., is extremely simple. The handle 2 is always in fixed position relative to the depending tubular member or sleeve 4; these two parts preferably being arranged at right angles, as clearly shown in the drawings. When the operator takes the device in his hand, the horizontal handle rests on his fingers, and the sleeve 4 projects downwardly through his fingers. With the tool in this position it is only necessary to lower the hand until the foot 5 strikes the floor or base 22 of the chassis, and then force the foot under the bottom of the tube; the position of the parts now being as illustrated in Figure 2. In some cases it is necessary to tip a tube slightly for the insertion of the foot 5.

The parts being in the position shown in Figure 2, it is only necessary to press down on the lever 1 to move it about the upper end of the spindle; the ball-shaped head 9 on the spindle 50 acting as a fulcrum for the lever. This leverage movement lifts the handle 2 and with it the attached tubular member with its foot 5. Of course the pointed end 6' of the spindle remains in engagement with the floor 22 of the chassis. This action results in lifting the tube vertically; its removal being easy, quick and certain. It should be mentioned at this point that when the device is operated to remove a tube, it is usually necessary to press a finger of the other hand against the opposite upper end of the tube to maintain it in substantially vertical position during removal. The position of the parts when the device has been operated to remove a tube is shown in Figure 3.

The device is now released, whereupon the spring 15 forces the lever 1 away from the grip 2, to thereby draw the lower end of the spindle 6 within the tubular member 4; the upper movement of the lever and spindle being limited as hereinbefore described.

As stated above, in the removal operation, the lever 1 fulcrums about the ball-shaped head 9 on the upper end of the spindle. This and the associated parts constitute one of the important improvements in the combination, over the dis-

closure of the tool disclosed in our above-mentioned application Serial Number 755,564, of which this application constitutes a continuation in part. When the lever 1 is depressed, to lift a tube, the base of the screw 11 rests upon and rocks about the curved upper surface of the head 9 producing an unusually smooth operation, and the relative movement between the spindle 6 and the lever 1 is taken care of by the ball-shaped head 9 and its seat 8 in a manner to augment the smoothness of operation. And the washer 14 having a cross-sectional curvature the same as the curvature of the lever, to fit neatly thereabout, prevents any interference of the spring in the smoothness of operation. And in this construction it is apparent that the parts cannot become separated accidentally, but the tool can be easily disassembled by removal of the screw 11.

From the foregoing description it will be apparent that we have devised a very simple and inexpensive tool which greatly facilitates the removal of tubes, vibrators and the like, however limited the working space may be, and regardless of the corroded condition of the parts or the heated condition of the tubes or the fragility thereof.

Having fully described the invention, what we claim is:

1. A tool for removing radio tubes including a slender tubular member adapted to be inserted within restricted spaces in a set, a foot at the lower end of the tubular member and extending laterally therefrom, said foot shaped to engage under a tube, a spindle housed within the tubular member and adapted to engage the floor of the chassis, the upper end of the spindle extending beyond the tubular member, a hand lever operable to lift the tubular member, said lever having

a cavity and an opening from the cavity through the lower side of the lever, the upper end portion of the spindle passing through said opening, a rounded head on the extreme upper end of the spindle and housed within the cavity, the diameter of the head being greater than the diameter of the opening, and said lever fulcrumed about the rounded head on the spindle.

2. A tool for removing radio tubes including a slender tubular member adapted to be inserted within restricted spaces in a set, a foot at the lower end of the tubular member and extending laterally therefrom, said foot shaped to engage under a tube, a spindle housed within the tubular member and adapted to engage the floor of the chassis, the upper end of the spindle extending beyond the tubular member, a hand lever operable to lift the tubular member, a rounded head on the upper end of said spindle, said lever having a cavity, the rounded head seated in said cavity, a plug or the like closing the upper end of said cavity, said plug engaging and rocking about the rounded head on the spindle in the operation of said lever.
